UNITED STATES PATENT OFFICE.

HAROLD A. MANDERSON, OF CINCINNATI, OHIO, ASSIGNOR TO THE PROCTER & GAMBLE COMPANY, OF CINCINNATI, OHIO, A CORPORATION OF OHIO.

CAN CLOSURE.

Application filed September 15, 1925. Serial No. 56,521.

My invention relates to the general art of leakproof cans and particularly to a novel closure for a can which shall be oil-proof and air tight.

5 It is the object of my invention to provide a can having a compression lid which shall be protected from leakage of oil or lard-like products packed in the can by the interposition of a gasket made of cellulose hydrate 10 which is a nitrated wood pulp product free of pores and fibres.

In the art can closures have been provided with compression lids in which a paper, cloth or parchment sheet has been seamed within 15 an annular ring and the joint between the ring and the body of the can, and compression tops have been provided which have been adapted to fit within the annular ring so that the general structure of my closure is well 20 known.

For a long time attempts were made to utilize known structures to provide an oil-proof and air tight seamed closure but until my discovery cans made in accordance with known 25 structures have been neither oil-proof nor air tight.

In packing a material such as edible oils and fats, three conditions require a completely hermetically sealed can. In the first 30 place the closure must be proof against oil leakage. It is well known that oil will leak through a joint which will retain water and a great variety of semi-solid products such as paint so that attempts to utilize materials 35 suggested in the prior art were unsuccessful because they were not oil-tight. The provision therefore, of a new type of closure was paramount in case the joints were to be oil-tight. Secondly materials which are subject 40 to oxidation are preserved much longer in their original sweet state if they are packed in an air-tight can. Lastly the closure must be provided with a gasket which is sufficiently pliable to seam in with the metal of 45 the cans and provide a readily compressible joint which will have enough natural resistance and tenacity to resist leakage strains in uncompressed portions. The gasket material must also be sterile so as not to contaminate an otherwise sterile food product. Preferably the gasket should also be transparent to reveal the contents of the can.

Considering the above requirements it should be noted that the several advances

made in the art by my novel structure provide 55 a degree of nicety heretofore unknown.

Referring now to the drawings in which I have illustrated a can having a preferred type of closure:

Figure 1 is a sectional view showing the 60 several parts prior to assembly.

Figure 2 is a sectional view with the parts assembled.

Generally indicated at 1 is the body of the can for which is provided an annular ring 65 member 2 having an opening 3 of sufficient size to retain the compression lid shown at 4. A cellulose hydrate gasket 5 of slightly larger diameter than the body of the can is further provided and in seaming the annular 70 ring onto the body of the can this gasket is crimped within the outer rim of the ring member and the bottom annular lip of the body of the can, preferably with a double overlapped crimp as shown, providing five 75 thicknesses of metal and three of cellulose hydrate. The lid for the can is provided by a regular type can bottom 6 having an outer annular flange portion adapted to be seamed to the body of the can after filling. 80

The can is preferably manufactured in the can factory with the cellulose hydrate gasket seamed within the annular ring member and the compression top in place. The can is then delivered to the packer who fills 85 the can from the bottom side and then seams in the bottom of the can. By reversing the labels on the cans it will be obvious that the can will be packed in cases in a reversed manner to that in which the cans are filled, so that 90 the consumer will naturally remove the compression lid and break the cellulose hydrate gasket just as if the can had been filled right side up.

The material packed in accordance with 95 such a can structure will be exposed in the natural sweet state in which it was packed and the cellulose hydrate gasket being readily penetrable may be cut out with a spoon or other utensil with which the contents are to 100 be removed.

It should be further understood that the cellulose hydrate gasket not only provides a seamed joint between the flange of the annular ring and the body of the can, but it also 105 keeps the oil or fat within the body of the can from coming in contact with the joint between the compression lid and the inner

- flange of the annular ring until after the gasket has been broken. Can closures which are air tight and oil tight may be provided by seamed annular edges of tin against tin so that the provision of a cellulose hydrate gasket would be unnecessary excepting with a compression lid, as it is particularly this type of closure which has heretofore been impractical.
- 10 The cellulose hydrate being of such film like structure is readily fractured so that if the disc was not spaced from the friction lid after the can was filled, an oily product, which, at the time of filling, is substantially free flowing, would induce a tendency to squeeze the cellulose hydrate disc up into the opening between outer wall of the top and the inner wall of the ring member. The air pocket formed between the lid and disc forms 20 an air cushion which resists the tendency of the material within the can forcing the cellulose hydrate into positions which with storage and handling of the can would tend to cause a fracture of the disc.

Having thus described my invention, what I claim as new and desire to secure by Letters Patent, is:—

1. A compression top can closure comprising in combination with a can body and an annular ring member with an aperture adapted to retain a compression top lid, a cellulose hydrate disc seamed between the outer edges of the annular ring and the body of the can, said disc retained in interspaced position from the compression top lid when said lid is in compressed position within the aperture in the ring member.

2. A hermetically sealable can having a bottom portion provided with frictionally retained closing means, a top adapted to be hermetically sealed, and a cellulose hydrate disc extending across and seamed to the body of the can interspaced from the frictionally closing means, said disc adapted to form an oil-proof, leak-proof wall inhibiting the passage of material from the can to the frictionally closing means.

HAROLD A. MANDERSON.
